UNITED STATES PATENT OFFICE.

ELMER E. KRUMBEIN, OF WOMELSDORF, PENNSYLVANIA.

DIRIGIBLE LIGHT.

1,133,292.

Specification of Letters Patent. Patented Mar. 30, 1915.

Application filed October 2, 1914. Serial No. 864,685.

To all whom it may concern:

Be it known that I, ELMER E. KRUMBEIN, a citizen of the United States, residing at Womelsdorf, in the county of Berks and State of Pennsylvania, have invented a new and useful Dirigible Light, of which the following is a specification.

This invention relates to dirigible lights of that type especially designed for use in connection with motor vehicles.

One of the objects of the invention is to provide means under the control of the driver whereby either or both of the lights can be turned relative to the vehicle on which they are mounted so as thus to cast rays of light in any desired direction irrespective of the direction in which the vehicle is traveling.

A further object is to provide means for locking the lights against movement until it is desired to actuate them.

Another object is to provide operating mechanism which is simple, durable and compact, inconspicuous, and which can be manipulated readily.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of a motor vehicle having the present improvements combined therewith. Fig. 2 is an enlarged plan view of a portion of the mechanism constituting the present invention, the light being removed. Fig. 3 is an enlarged side elevation of the lamp support and the mechanism thereunder. Fig. 4 is a section on line A—B Fig. 3. Fig. 5 is a plan view of the controlling levers in their normal positions. Fig. 6 is a similar view showing said levers shifted out of their normal positions.

Referring to the figures by characters of reference C designates a portion of a motor vehicle, and in the structure illustrated the mud guards D constitute supports for the dirigible lamps constituting the present in-

vention although it is to be understood that these lamps can be mounted at any other points desired.

The present invention includes a base 60 plate 1 adapted to be bolted or otherwise secured upon its supporting structure and arranged on this base plate are superposed bearing plates 2 and 3 which may be held together in any manner desired. Journaled 65 between the plates 2 and 3 is a segmental gear 4 having an arm 5 extending inwardly therefrom beyond the edges of the plates 2 and 3. Gear 4 meshes with a small gear 6 secured to a stem 7 which is mounted for 70 rotation within the plate 3 and is secured at its upper end to a disk 8 arranged upon said plate 3. This disk is provided with upstanding arms 9 adapted to be secured to a suitable lamp, shown for example at 10, 75 it being understood that any kind of a lamp may be mounted on and secured to the disk 8.

Disk 8 is provided at diametrically opposed points with stop shoulders 11 and 12 and upstanding from the plate 3 are stop 80 pins 13 and 14. These pins are so positioned that when the lamp 10 is throwing rays forwardly, shoulder 12 is in engagement with pin 14. However, after the lamp has completed a one quarter turn outwardly from 85 its normal position, shoulder 11 will come into contact with stop pin 13.

When shoulder 12 is in engagement with stop pin 14, shoulder 11 is engaged and held by a locking dog 15 pivotally mounted on 90 the plate 3 and held normally in engaging position by a spring 16. One end of dog 15 is connected by a wire 17 or the like to one end of a bell crank lever 18 journaled upon plate 3 near the inner side thereof and 95 secured to the other arm of the bell crank lever 18 is an actuating cord 19 which extends rearwardly through the dashboard E of the vehicle and is connected to a lever 20 fulcrumed upon the lower portion of the 100 dashboard, where it can be reached readily by a foot of the driver. Lever 20 is disposed directly back of another corresponding lever 21, the two levers being so positioned that after the foot engaging end 22 105 of lever 20 has been pushed back a predetermined distance, it will strike the corresponding end 23 of lever 21 so as to then cause said lever 21 to shift out of its normal position. Lever 21 has a tube 24 pivotally 110 connected to it and extending forwardly through the dashboard E, this tube 24 being

secured, at its front end, to the inwardly extending arm 5 of the segmental gear 4. A spring 25 is also connected to the arm 5 and to the plate 3, this spring exerting a constant forward pull upon the arm 5 so as thus to hold shoulder 12 pressed against pin 14 and lamp 10 in position to direct rays of light forwardly. The cord 19 is extended through the tube 24.

10 It is to be understood that where two lamps are used upon a vehicle, each of them will be provided with mechanism such as herein described, there being two levers 20 and 21 provided for each lamp, and these 15 two pairs of levers being oppositely disposed as shown in Fig. 1, both pairs being positioned where the levers of one pair can be actuated readily by one foot, while the levers of the other pair can be actuated readily by the other foot.

Should it be desired to shift the left lamp so as to throw rays of light laterally from the machine while the machine is moving forward or under any other conditions, it 25 would merely be necessary for the driver to press against the end 22 of lever 20. Before said end comes into contact with the end 23 of lever 21, the cord 19 will pull on lever 18 and thus shift dog 15 so as to unlock the 30 disk 8. Immediately subsequent to this unlocking operation, lever 21 is actuated in the manner described and will pull through tube 24 upon arm 5, thus actuating the gears 4 and 6 and causing the disk 8 to rotate any 35 desired distance or until the shoulder 11 comes against the stop 13. The speed of this rotation as well as the extent of rotation can be easily controlled by the driver. By using the right foot upon the other set of 40 levers 20 and 21, the other lamp can be unlocked and rotated. Thus it will be seen that it is possible, by means of the mechanism herein described, to direct rays of light forwardly or laterally from the vehicle irrespective of the direction in which said vehicle may be traveling.

What is claimed is:—

1. The combination with a revoluble lamp support, and means for locking the support

against rotation, of a lever, support rotating 50 mechanism, a connection between said mechanism and the lever, yielding means for holding said mechanism and the lamp support normally in a predetermined position, a second lever, and means operated by said 55 second lever for unlocking the lamp support, said second lever being adapted, during its actuation in one direction, to successively unlock the support and actuate the rotating mechanism.

2. The combination with a lamp support mounted for rotation, and means for locking said support against rotation, of a gear revoluble with the support, a second gear meshing therewith, an arm extending from said 65 second gear, a lever, a connection between the lever and arm, yielding means for normally holding the gears in predetermined positions, a second lever, means connected thereto for unlocking the support, said second lever being adapted, during its movement in one direction, successively to unlock 70 the support and to actuate the first mentioned lever.

3. The combination with a lamp support 75 mounted for rotation, and means for locking said support against movement, of a gear revoluble with the support, another gear meshing therewith, an arm extending from the last named gear, a lever, a tubular 80 connection between the lever and arm, yielding means engaging the arm for holding the lever and lamp support normally in predetermined positions, a second lever, and a connection between said second lever and the 85 locking means, said connection being extended through the tubular connection, the said second lever being adapted, during its movement in one direction, successively to unlock the support and to actuate the first 90 named lever to rotate the support.

In testimony that I claim the foregoing as my own, I have hereto affixed my signature in the presence of two witnesses.

ELMER E. KRUMBEIN.
